J. H. A. KRAUSS.

KEY BOLT.

APPLICATION FILED OCT. 27, 1913.

1,170,914.

Patented Feb. 8, 1916.

UNITED STATES PATENT OFFICE.

JOHN H. A. KRAUSS, OF BOSTON, MASSACHUSETTS.

KEY-BOLT.

1,170,914.

Specification of Letters Patent.

Patented Feb. 8, 1916.

Application filed October 27, 1913. Serial No. 797,491.

To all whom it may concern:

Be it known that I, JOHN H. A. KRAUSS, a citizen of the United States, residing at Boston, in the county of Suffolk and State 5 of Massachusetts, have invented certain new and useful Improvements in Key-Bolts, of which the following is a specification.

My invention relates to key bolts and more particularly to that class of bolts used in 10 connection with an ordinary lock.

The primary object of my invention is to provide a bolt having means thereon for guarding a key hole to prevent the key from being removed from the lock.

Another object of my invention is to provide a novel means for holding the bolt in 15 closed or locked position.

A further object of my invention is to provide a bolt that is simple in construction, 20 efficient in operation, and which can be manufactured and put upon the market at a minimum cost.

A still further object of my invention is to provide a device in connection with the 25 key hole so that when the same is in closed position it will also close the key hole.

Other objects as well as the nature, characteristic features, and scope of my invention will be clear from the following description taken in connection with the accompanying drawings and pointed out in the claims.

In the drawings: Figure 1, is a front elevational view of my invention in locked or 35 closed position. Fig. 2, is a front elevational view of my invention in open position. Fig. 3, is a top plan view of my invention applied to a door showing the upper edge of the door partly broken away. Fig. 4, is a transverse, 40 sectional view taken on line 4—4 of Fig. 3.

Referring more particularly to the drawings in which similar reference numerals designate like or corresponding parts throughout the different views, the numeral 45 1, represents a base plate which has formed thereon a plurality of transversely extending spaced apart parallel yokes 2, and disposed adjacent the outer end of the plate centrally between the yokes is a transversely extending key hole 3. Slidably arranged upon the base plate 1, and guided and supported during its movement by the yokes 2, is a locking plate 4, which plate is provided adjacent its inner end with a knob 5, which 50 also serves as a stop by contacting with the inner edge of the inner yoke, thus limiting

inward movement of the locking plate 4. The locking plate 4, is provided adjacent its opposite end with a key hole 6, which, when in the position as shown in Fig. 2, alines with the key hole arranged in the base plate 1. Extending inwardly at right angles from the upper end of the key hole 6, is a longitudinal slot 7.

For the purpose of locking the bolt in 65 position I have provided the locking plate 4, with a raised portion 10, which forms a shoulder 11, adjacent the knob 5. Disposed in the depressed portion 8, of the base plate 1, is a flat spring 9, which bears against the locking plate 4, beneath the raised portion 10.

In applying my device to the door 12, the base plate 1, is secured by means of screws or the like fastening members 13, so that the 75 key hole 3, alines with the key hole 14 in the lock 15, on the door 12, as clearly shown in Fig. 3, of the drawings.

The operation of my device is as follows: 80 The key 16, having a flat shank, is inserted in the key holes of the plate and the lock when they are in alinement, and by grasping the knob 5, pushing the locking plate forward, the slot 7, engages the flat shank of the key 9, and is locked in place and held in this position by the spring 15, which forces the locking plate 4, outwardly so that the shoulder 9, and the knob 5, are engaged upon the opposite edges of one of the yokes 2. To open, the locking plate 4, is moved 85 inwardly against the tension of the spring and pulled backward. It is obvious that a key having a round shank, may be flattened by filing or the like so that it may be engaged by the slot in the locking plate.

It is obvious that when the bolt is in locked position, the outer end of the locking plate is engaged in the socket member in the door frame.

It will be obvious to those skilled in the 100 art to which my invention relates that modifications may be made in detail without departing from the spirit and scope of my invention.

Having thus fully described my invention, 105 what I claim as new and desire to secure by Letters Patent is:

In combination with a lock having a key hole and a key associated therewith, a base plate mounted adjacent said lock and provided with a key hole, a plurality of transversely extending yokes upon said base 110

plate, a relatively flat locking plate slidably supported by said yokes, said locking plate being provided with a key hole for registration with the key hole of the base plate 5 and lock, said locking plate being further provided with a longitudinally extending slot terminating upon the upper end of said key hole and adapted to receive said key, a transverse abutment upon said locking 10 plate, a knob upon said locking plate for facilitating the operation thereof, said base plate provided with a longitudinally extending recess, and a bow spring mounted in said recess and bearing against said locking plate

for yieldingly and releasably holding said 1 locking plate in various adjusted positions for maintaining said abutment in engagement with one of said yokes for preventing relative sliding movement of the plates and consequently maintaining said key in said 2 lock.

In testimony whereof I affix my signature in presence of two witnesses.

JOHN H. A. KRAUSS.

Witnesses:

WILLIAM E. MOCK,
EDMUND G. WHITE.
